CLAIM

We claim the ornamental design for a thermal container, as shown and described.

DESCRIPTION

FIG. 1 depicts a perspective view of a thermal container.

FIG. 2 depicts a front elevation view of a thermal container.

FIG. 3 depicts a rear elevation view of a thermal container.

FIG. 4 depicts a side elevation view of a thermal container.

FIG. 5 depicts an opposite side elevation view of a thermal container.

FIG. 6 depicts a top plan view of a thermal container.

FIG. 7 depicts a bottom plan view of a thermal container.

FIG. 8 depicts a perspective view of a thermal container.

FIG. 9 depicts a front elevation view of a thermal container.

FIG. 10 depicts a rear elevation view of a thermal container.

FIG. 11 depicts a side elevation view of a thermal container.

FIG. 12 depicts an opposite side elevation view of a thermal container.

FIG. 13 depicts a top plan view of a thermal container.

FIG. 14 depicts a bottom plan view of a thermal container.

FIG. 15 depicts a perspective view of a thermal container.

FIG. 16 depicts a front elevation view of a thermal container.

FIG. 17 depicts a rear elevation view of a thermal container.

FIG. 18 depicts a side elevation view of a thermal container.

FIG. 19 depicts an opposite side elevation view of a thermal container.

FIG. 20 depicts a top plan view of a thermal container.

FIG. 21 depicts a bottom plan view of a thermal container; and,

FIG. 22 depicts an exploded perspective view of a thermal container.

The broken lines in the drawings illustrate environmental structure on the article and form no part of the claimed design.

The cup, closure and container are shown separately in the drawings for clarity of illustration.
